INVENTOR.

Walter Bruce Wills,

BY
Henry J. Brewington.

ATTORNEY.

UNITED STATES PATENT OFFICE.

WALTER BRUCE WILLS, OF BALTIMORE, MARYLAND.

SOAP-TRAY.

1,320,814.

Specification of Letters Patent.

Patented Nov. 4, 1919.

Application filed July 17, 1919. Serial No. 311,507.

To all whom it may concern:

Be it known that I, WALTER BRUCE WILLS, a citizen of the United States, residing at Baltimore, State of Maryland, have 5 invented certain new and useful Improvements in Soap-Trays, of which the following is a specification.

This invention relates to devices designed for holding soap, and adapted to be supported over a sink, laundry tub, lavatory basin, and the like.

The invention has for its object to provide a soap holder which need not be fastened to a wall, but which is provided with a novel 15 and improved means whereby it can be supported by the hot and cold water faucets of the sink or other appliance, the holder being placed between the faucets, and the supporting means being capable of adjustment 20 according to the distance between the faucets, to enable the holder to be attached to differently spaced faucets.

With the object stated in view, the invention consists in a combination and arrangement of parts to be hereinafter described and claimed, and in order that the same may be better understood, reference is had to the accompanying drawing forming a part of this specification.

30 In the drawing—

Figure 1 is a perspective view of the device supported by and between two faucets; Fig. 2 is a bottom plan view of the device; Fig. 3 is a side elevation thereof, and Fig. 35 4 is a cross section.

Referring specifically to the drawing, the soap holder is a shallow, open-work tray or dish constructed entirely of wire, and having a rectangular or other desirable contour. 40 The bottom of the holder is composed of spaced and parallel wire cross bars 5 and longitudinal wire bars 6 having upward bends at their ends which are attached to a wire frame 7. The tray is suitably dimensioned to support one or more pieces of soap, and to seat between the hot and cold water faucets 8 of the sink, basin, or other appliance, as shown in Fig. 1, and at the ends of the tray are hooks which are engageable 45 with the faucets for holding the tray suspended therebetween, said hooks being so

constructed that they may be engaged over the body of faucets of various styles without interfering with the operation thereof.

Inasmuch as the faucets of sinks, laundry 55 tubs, basins and similar appliances are spaced apart various distances, the hooks hereinbefore referred to are made adjustable so that they may be spread and thus set according to such spacing of the faucets. This 60 adjustment is effected by having the hooks slidably connected to the tray, so that they may be extended from the ends thereof the required distance to properly engage the faucets. For this purpose, each hook is 65 formed of a single piece of wire which is bent intermediate its ends to form two laterally spaced shanks 9 connected at one end by a curved bend 10, and having said end bent into the shape of a hook, as shown at 70 11. Two hooks are provided, each having shanks as described. One hook is at one end of the tray and the other hook is at the other end of the tray. The shanks of the hooks are slidably connected to the bottom 75 of the tray, so that they may be extended more or less from the ends of the latter according to the spacing of the faucets. This sliding connection is effected by making downward bends 12 in some of the bottom 80 cross bars 5 of the tray, said bends being dimensioned to seat the shanks 9. The inner ends of the shanks 9 are bent down, as shown at 13, to form stops which coöperate with the inner ones of the aforesaid cross 85 bars to limit the outward movement of the hooks, and thus prevent the latter from being detached from the tray. The shanks 9 are beneath the cross bars 5 which are without the seats 12, whereby the shanks are 90 held in the seats and prevented from becoming detached from the tray, and the seats prevent the shanks from slipping transversely of the tray bottom.

It will be evident from the foregoing that 95 there has been provided a soap holder which is simple in construction, and the supporting means of which are readily adjustable according to the spacing between the faucets which are to support the device.

I claim:

A soap holder comprising a tray, and sup-

porting hooks, at opposite ends thereof adapted to engage a faucet, said hooks having shanks which are slidably connected to the bottom of the tray and adjustable to hold the bottom of the tray and adjustable to hold the hooks projected variable distances from the ends of the tray, the bottom of the tray having cross bars provided with downward bends, seats for the hook shanks and said

tray bottom having other cross bars positioned above said shanks.

In testimony whereof I affix my signature in the presence of two witnesses.

WALTER BRUCE WILLS.
